UNITED STATES PATENT OFFICE.

OTTO KRISTIAN SØRENSEN AND ALFRED JENS PETER ÖSTERGAARD, OF COPENHAGEN,
DENMARK.

PACKAGE-TIE.

1,300,502.

Specification of Letters Patent. Patented Apr. 15, 1919.

Application filed December 29, 1916. Serial No. 139,607.

To all whom it may concern:

Be it known that we OTTO KRISTIAN SØRENSEN, engineer, and ALFRED JENS PETER ÖSTERGAARD, sub-postmaster, citizens of the 5 Kingdom of Denmark, residing at Copenhagen, in the Kingdom of Denmark, have invented certain new and useful Improvements in Package-Ties, of which the following is a specification.

10 There are already several known forms of apparatus for tying up parcels, bunches of letters or papers, etc., by means of cord, string, tape, or the like.

Such apparatus consist of, for instance, a 15 plate of metal or other suitable material provided with a hole, a pin, or the like, for holding one end of the cord or string, and with a clamp device for holding the other end of the cord or string.

20 All these known apparatus, however, generally have several disadvantages which make them more or less impracticable. The clamps do not hold the cord or string tightly enough, and it is liable to slip or, at all 25 events, to be pulled out of its proper position. The apparatus, and especially the clamp device, have too many projecting parts, which easily catch hold of other parcels or other objects adjacent to the parcel to be 30 tied, and thus it frequently happens that the clamp device is opened, the string slips out, and the parcel is undone.

It is the object of the present invention to 35 remedy these disadvantages by giving the clamp device a special shape, so that the string is held securely, and by the absence of all projecting parts which can catch hold of foreign objects thereby causing the parcel to be undone. It is especially important in this 40 invention that the resilient part of the clamp device is situated below the stationary part, and is therefore not interfered with when the apparatus happens to touch any foreign objects.

45 The drawing shows two different forms of construction for this invention. Figure 1 is a top view of one form of construction. Fig. 2 is a section through the same along the line I.—I. in Fig. 1. Fig. 3 shows the 50 apparatus with the strings wrapped around a parcel, or the like. Fig. 4 is a top view of another construction of this invention.

The apparatus, which may preferably be made of one single piece of plate, consists

of a plane part 2 and a projecting ear 4 on 55 which should be placed the thumb of the person using the apparatus, and therefore this part 4 may be provided with a hole 5 or with corrugations, which will prevent the thumb from slipping on the plate. Furthermore 60 the plane part 1 has a notch 6, a projecting lug 7, which serves as a guide for the single string 8 (Fig. 3), when it is to be wrapped around a parcel, a bunch of letters, or the like, and a flap 12 provided with a 65 hole or a pin 13, which serves to hold the string or cord.

The plate 2 is prolonged into a tongue 14, which is bent inward under the plate 2 proper (see Fig. 2) and furnished with a 70 boss 15, which projects up through an opening 16 in the plate 2. Instead of this opening there may, of course, be a bulge in the plate 2 corresponding to the shape of the boss 15. The tongue 14 presses resiliently 75 up against the lower side of the plate 2. Between the ear 4 and the plate 2 there is a notch 17, and between the flap 12 and the plate a notch 18, which serves to guide the string or cord, as set forth in the following. 80

The plate 2 lies on a higher plane than ear 4, the lug 7, and the flap 12.

In the form of construction set forth in Fig. 4, there are two bosses 15 on the tongue 14 and two corresponding openings 16 in 85 the plate 2.

The apparatus with the string held fast in the hole 13 is used in the following manner for tying up for instance a bunch of letters.

The apparatus is laid on the top of the bunch and held there for instance by the user's thumb, which is pressed on the part 4. As shown in Fig. 3, the string or cord is first passed for instance lengthwise 90 around the bunch of letters till it reaches the notch 6, into which the string is passed, so that it will lie under the bend of the plate 2. Then the direction of the string is altered so that it can be wrapped crosswise 95 around the bunch, after which the end of the string is finally secured in the clamp device by passing it into the notches 17 and 18, as shown in Fig. 3.

This is accomplished by passing the string 100 8 in between the tongue 14 and the plate 2, so that it will rest on the top of the boss or bosses 15 and by means of the resili-

ent tongue 14 it is pressed up into the opening or openings 16, where it is held securely fast.

If it is desired to undo the parcel again, 5 the string is pulled out from the intermediate space between the plate 2 and the tongue 14, and the apparatus can then be removed and used for a new parcel or bunch of letters.

10 We claim—

1. A package tie, comprising a single piece of resilient sheet material bent upon itself to form adjacent integral members, one of which is formed with a bulged portion 15 pressed inwardly therefrom toward the second member and beyond the plane thereof, the second member being formed to receive said bulged portion, and the latter being held by the resilience of the material 20 in gripping engagement with said second member.

2. A package tie as claimed in claim 1, wherein the second member of the tie is formed with an opening and the bulged portion 25 of the first member is yieldingly pressed into said opening and into gripping engagement with the edges thereof.

3. A package tie as claimed in claim 1, wherein the second member of the tie is

provided with side extensions lying in a 30 plane substantially parallel with that of said member and spaced therefrom, and the first member of the tie lies in a plane between those of the second member and its extensions.

35 4. A package tie as claimed in claim 3, wherein the portion of the tie joining said members together lies between and projects beyond the portions joining the second member with its side extensions, the flexible 40 member of the tie being passed under the first mentioned portion and around one of the other portions to change its direction.

5. A package tie as claimed in claim 3, 45 wherein the portions of the tie joining the second member with its side extensions are notched to guide the flexible member of the tie into position between the bulged portion of the one member and the corresponding portion of the other member.

50 In testimony whereof we affix our signatures in presence of two witnesses.

OTTO KRISTIAN SØRENSEN.

ALFRED JENS PETER ÖSTERGAARD.
